UNITED STATES PATENT OFFICE

106,720

DESIGN FOR A DRESS ENSEMBLE

Phil Cohen, New York, N. Y.

Application September 27, 1937, Serial No. 71,812

Term of patent 3½ years

To all whom it may concern:

Be it known that I, Phil Cohen, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The rear jacket portion is conventional, and is shirred as shown in Figure 1.

I claim:

The ornamental design for a dress ensemble, substantially as shown and described.

PHIL COHEN.
